[57] CLAIM

The ornamental design for a patient transfer device, as shown and described.

DESCRIPTION

FIG. 1 is a top, side and end environmental perspective view of a patient transfer device showing my new design, the portion of the figure shown in broken lines representing a patient, transfer staff and ancillary equipment and forming no part of the claimed design;

FIG. 2 is a top plan view thereof;

FIG. 3 is a bottom plan view thereof;

FIG. 4 is a side elevational view thereof; and,

FIG. 5 is an end elevational view thereof, the opposite end being a mirror image.

Portion of cords of the patient transfer device shown broken away indicate indeterminate length and for convenience of illustration.

FIG. 1

FIG. 2

FIG. 3

FIG. 4

FIG. 5
